UNITED STATES PATENT OFFICE.

JOHN BURNS, OF NEW YORK, N. Y.

DENTAL MOLDING APPARATUS.

1,146,550.

Specification of Letters Patent. Patented July 13, 1915.

Application filed February 18, 1915. Serial No. 9,065.

To all whom it may concern:

Be it known that I, JOHN BURNS, a citizen of the United States, residing in the borough of Queens of the city of New York, State of New York, have made certain new and useful Improvements in Dental Molding Apparatus; and I hereby declare the following specification to be a description thereof, reference being had to the accompanying drawing.

The object of my invention is to provide a convenient and efficient means for taking impressions in the production of the various kinds of dental work, such as what is known as crown work, or the reproduction of saddle formation, and plates.

In the drawings: Figure 1 is a top view of my device showing the flask and compressor, made integral. Fig. 2 shows the compressor with the flask removed; Fig. 3 is a side view of Fig. 1; Fig. 4 is an interior view of one half of the flask; and Fig. 5 shows a modification of the device.

The principal part of the apparatus employed in my improvements comprises what may take the place of a flask in molding and is composed of two parts A and B. These parts are of the desired shape or size to suit the work being done.

C, represents generally a compressing device for manipulating the flask which for convenience, has two handles D, and D¹ secured together by means of a pin E passing through them, and having on one end a nut a. A locking arm G, is secured to one arm D, of the compressing tongs, by a swivel pin b, and is notched at the other end to engage a pin c, located on the other arm D¹.

The ends H, H, of the compressing device are made flat and provided with sockets or holes h, h, which will receive pins i, i, located on the base of the two halves or cups, A and B holding the molding composition. The holes are made to register with the pins and if desired retaining screw nuts n, n, may be employed to hold them in place. Or the cups may be integral with the tongs.

The shape and size of the two cups, or halves A and B will vary with the size of the pattern, or mold, of the work which is being used, but they should always conform to the requirements herein referred to; that is they should have two open sides, one of which faces the other half. When the two halves A and B are brought together ready to have the fusible metal poured, and are

fastened by the catch o, they may be removed and other cups of different size such as an oblong shape, be placed in position.

In the present practice of producing dental work such as crowns for individual teeth, or more extended work, covering the saddles of the gums or plates for the palate, the plaster cast or pattern is pressed down into a cup, or other receptacle containing molding composition and the composition is pressed around the pattern. The pattern is then lifted vertically out of the composition and the fusible metal poured directly into the cavity thus left in the molding composition contained in the cup. The cast so obtained is then filed or gone over, so as to have the proper shape and the gold covering then worked over it.

In my new method I discard the single receptacle for the molding composition and employ the two halves or cups A and B which I first fill with the molding composition pressing it into place and making the side or face of the composition in each of the halves where they will contact even and smooth. The exposed face of the composition is then dusted with a powder as indicated at t Fig. 4 sufficient to prevent the two portions of composition contained in the parts A and B adhering to each other when they come in contact. The model of the work in hand is then placed between the two halves A and B of the flask, after which the handles D and D¹, of the compressing tongs being worked together, the two cups or halves of the flask are closed upon the pattern and locked in position by means of the arm G. The molding composition is then pressed or packed down around the model or pattern by use of the fingers or otherwise at the exposed or open face of the flask. It will be understood that during this operation of pressing down the molding composition the two halves of the flask A and B, are firmly held together by the locked handles of the tongs.

I have found that the least movement of the two molding cups will cause defective work and therefore the locking bar G plays an important part in the operations of the device, by making a firm container during the operation of pressing down the molding composition so the two cups A and B, are substantially as firm as though it was a single receptacle.

After the composition has been firmly

pressed around the mold or pattern the arm 5 G is lifted and the two halves A and B of the flask will be drawn apart so that a cleavage of the molding composition takes place along the center leaving a half of the impression of the pattern in each of the parts A and B. The pattern having been removed, the handles of the compressing tongs are worked together again to bring 10 the opposing faces of the two halves of the flask closely against each other as in Fig. 1, and the arm G used to lock them again. The fusible metal is then poured into the flask. In this manner a more perfect cast of the 15 pattern is obtained.

It will be understood from the foregoing that in my new method two objects are obtained. First the pattern is not pushed down into the molding composition and secondly the pattern is not drawn out after the molding composition is pressed around it.

By my new method I obtain the advantages of the method of casting in sand and at the same time avail myself of the use 25 of a molding composition which is pressed around the pattern after it is in place.

I have shown and described the means I

prefer to use in bringing and holding together the two halves of the molding device, but I do not wish to confine myself 30 to the exact mechanism shown as the two halves of the flask, may be brought together and fastened by other analogous means, so long as there is an open portion at which the molding composition may be compressed 35 around the pattern after it is in position.

In Fig. 5 the two cups or halves of the flask are shown held together by catches o, o, and registering pins p, p, are employed on one cup with sockets p¹ in the other cup. 40

I claim as my invention:

In apparatus for making castings for dental work, molding cups A and B having pins i, i, and p, sockets p¹, and catch o in combination with jaws H, H, pivotally connected and provided with registering holes h, h, and manipulating arms D, D¹, substantially as and for the purposes shown and 45 described.

JOHN BURNS.
